United States Patent

Des. 238,942
Patented Feb. 24, 1976

238,942

VEHICLE BODY COVER

Herbert O. Dixon, Jr., 802 N. 8th St.,
Clear Lake, Iowa 50428

Filed Aug. 29, 1973, Ser. No. 392,734

Term of patent 14 years

Int. Cl. D12—16

U.S. Cl. D12—156

FIG. 1

FIG. 2

FIG. 3

FIG. 4

FIG. 5

FIG. 1 is a perspective view of a vehicle body cover showing my new design;

FIG. 2 is a side elevational view of FIG. 1;

FIG. 3 is a top plan view of FIG. 1;

FIG. 4 is a rear elevational view of FIG. 1; and

FIG. 5 is a front elevational view of FIG. 1.

I claim:

The ornamental design for a vehicle body cover, substantially as shown.
